RAIL SPLICE CLAMP

Raymond J. Chapman, Orange Township,
Noble County, Ind.

Application September 6, 1940, Serial No. 355,558

6 Claims. (Cl. 29—84)

This invention relates to improvements in rail splice clamps. More particularly, the invention relates to a device by means of which the splice plates to be secured to adjacent rail sections at a rail joint may be clamped in operative relation to the rail sections while the splice plates are being secured to the rail sections.

The primary object of the invention is to provide a device of this character which is novel and simple in construction, inexpensive to manufacture, and easy to operate.

A further object is to provide a device for clamping rail splice plates which shiftable carries a pin for aligning bolt receiving apertures of said splice plates and of the rails to be spliced during the operation of clamping the plates in operative relation to the rails.

A further object is to provide a device of this character comprising a pair of pivotally interconnected clamp members, wherein one of said members carries a slidable aligning pin, and the other of said members is forked to accommodate positioning of said pin in intersecting relation thereto.

A further object is to provide a device of this character by means of which splice plates are urged to operative position with respect to adjacent rails at a rail joint during the operation of clamping the plates to the rail.

A further object is to provide a unitary device of this character for maintaining an aligned relation between the apertures of splice plates on opposite sides of the web of a rail, and for clamping said splice plates to the rail while maintaining the alignment of said apertures.

Other objects will be apparent from the specification and appended claims.

In the drawing:

Fig. 1 is a perspective view of my new device. Fig. 2 is a transverse vertical sectional view of a rail and splice plate at a rail joint, and illustrates my clamp in side elevation with parts broken away.

Fig. 3 is a fragmentary side view illustrating the application of my clamp to splice plates at a rail joint.

Fig. 4 is a fragmentary top plan view of my clamp applied to splice plates at a rail joint.

Referring to the drawing, the numeral 10 designates one railroad rail section, and the numeral 11 a second rail section, which rail sections are abutted at 12 to form a joint. The rails 10 and 11 are of complementary construction and each comprises a base 13, a web 14 and a head 15. The rail sections are adapted to be rigidly secured in alignment by means of splice plates 16 positioned at opposite sides of said rails at said joint. The splice plates each comprise a web 17, a base portion 18 adapted to seat solidly upon the upper surface of one side of the rail.

base 13, and a head 19 adapted to fit solidly under one side of the rail head 15. The web 14 of each rail section is provided with a plurality of spaced apertures 20, and the webs 17 of the splice plates 16 are likewise provided with a plurality of similarly spaced apertures 21. The splice plates 16 are adapted to be rigidly secured at opposite sides of the rail in clamping relation thereto by bolts extending through said apertures 20, 21, and fastened by nuts 22.

For the purpose of clamping the splice plates to the rails 10 and 11 so as to positively align the heads 15 of said rails and at the same time to maintain alignment of the bolt holes 20 and 21 in said rails and splice plates preparatory to applying said bolts and nuts 22, I have provided a device of which one embodiment is illustrated in the drawing.

My device comprises a frame 25 comprising a pair of spaced, parallel, complementary, rigid, longitudinally curved flat bars 26. The curvature of these bars is substantially semi-circular, although it will be understood that various other shapes may be employed with equal facility. Bars 26 are rigidly interconnected substantially centrally of their length by a cross plate 27.

A lever 28 is positioned between the frame bars 26 adjacent one end thereof, and is pivoted thereto at 29. The lower end of the lever 28 is bifurcated, with the forks 30 thereof positioned laterally outwardly from the body of the lever. The forks 30 are bent forwardly in a curvature of approximately 90 degrees, and the free ends of the forks 30 are bent downwardly and outwardly to form hooked portions at 31. The convex faces of the forks are preferably toothed or serrated at 32 adjacent hook portions 31.

A bearing 33 is positioned between bars 26 adjacent the end thereof opposite lever pivot 29, and is pivotally connected thereto at 34. The bearing 33 has a bore extending centrally therethrough with the axis of said bore transverse to the pivot axis of the bearing. An elongated rigid pin 35 is slidably mounted in said bore. Pin 35 is preferably provided with an enlargement or collar 36 intermediate its ends.

The operation of the device is as follows: When the same is to be applied to the splice plates 16 at the rail joint 12, the lever 28 is pivoted to a position wherein it substantially engages the block 27. The ends 31 of the frame 25 are positioned against the lower outer edge of the base 18 of one splice plate 16, with the remainder of the frame 25 spanning the rail. The pin 35 is extended through one set of bolt receiving apertures 21, 20 in the splice plates and rail section, respectively. Thereupon the lever 28 is swung to the position illustrated in Fig. 2 to cause the hooked portion 31 at the lower free end of the lever to engage against the lower outer edge of the base

18 of the opposite splice rail. Thereafter, the lever is pulled to tighten the clamp and to cause the respective splice plates 16 to seat firmly against the opposite sides of the rail sections thereby bringing said rail sections into alignment. The clamp is held in this clamping position while the bolts and nuts 22 are applied through the remaining aligned sets of apertures to secure the splice plates to the rail ends.

It will be observed that the alignment of the apertures in the splice plates is first achieved while the splice plates are loosely arranged with relation to the rails, and that thereafter as the clamp is tightened to urge the splice plates firmly against the opposite sides of the rail and to align the joint ends of the rails, the alignment of the plate apertures remains constant. Thus one of the primary advantages of this construction is that it eliminates any necessity for separately manipulating aligning pins, and that once the pin 35 is applied in the plate and rail apertures, it remains in place during the clamping operation without requiring special handling thereof.

Still a further advantage of the construction is the fact that the aperture alignment of the plates is effected at the point at which the splice plates are clamped, so that only one set of bolt receiving apertures is obstructed during the application of the splice plates, so that the remaining sets of apertures may receive bolts to permit easy and rapid securing of the splice plates to the rail.

By reason of the free sliding of the aligning pin 35 in the bearing 33, it is desirable to incorporate the collar 36 so that the pin may be slid forwardly until said collar abuts the splice plate to limit its movement at desired operative position. It will be observed that the forked formation of the lower end of the lever 28 permits the lever to operate without interference from the projecting free end of the pin 35, and that the forked end freely straddles said pin.

Of further importance for the purpose of facilitating application and removal of the clamp and of the pin 35, is the provision of pivot 34 for the pin-receiving bearing 33. It will be observed that this pivot permits the pin to be inserted before the clamp frame is operatively positioned with relation to the rail and the plates without hindering the necessary manipulation of the parts.

The outward curvature of the portion 30 of the lever is important with reference to the respective positions which the lever pivot 29 and the hook portion 31 of the lever assume. Additionally, the curvature permits the lever portions to overlie the base of the splice plates and to assist in holding the lever-engaged splice plate in operative position during initial operation of the clamp. The serrations or teeth 32 on the forks assist in giving a solid engagement between the lever and the splice plate, and prevent sliding of the lever hook 31 relative to the splice plate. Also, the particular form of the lever and the resultant location of its pivot 29 substantially directly above the plate engaging hook 31, permits clamping operation of the lever to impart an upward component of force to the base of the splice bar, and hence assure its solid seating against the side of the rail.

If desired, a bolt (not shown) may be threaded on the outer end of the pin 35, or any suitable head may be applied thereon, for the purpose of confining movement of the pin between the col-

lar 36 and said head, and thereby holding the parts of the device together at all times.

The shape of the lever 28 with particular respect to the bend of the forks 30 relative thereto may be varied within a wide range. Thus the bend of said forks 30 may be such that the inner ends of said forks are adapted to engage and press against the web 17 of the splice bar 16 which is engaged by the lever. Such a construction involves contact of the splice bar by the lever at two points, namely at the web 17 by the inner ends of the forks 30 and at the outer edge of the base 18 thereof by the hook lever portions 31. Hence the application of pressure by the lever occurs on each side of the bolt hole 21 and pin 35, and assures proper positioning of the splice plate relative to the rail with a minimum opportunity for binding or dislocation of the splice plate upon operation of the clamp.

I claim:

1. A rail splice clamp comprising a curved frame adapted at one end thereof to engage one rail splice plate, a lever pivoted to the other end of said frame and including a forked portion adapted to engage a rail splice plate opposite said first plate, and an aligning pin slidably carried by said frame adjacent its rail engaging end and adapted to be freely received between the forks of said lever.

2. A rail splice clamp comprising a curved frame adapted at one end thereof to engage one rail splice plate, a lever pivoted intermediate its ends to one end of said frame, one end of said lever being forked and the ends of said forks being inwardly bent to engage a rail splice plate opposite said first splice plate, and a pin pivotally and slidably carried by said frame and adapted to pass between said forks.

3. A rail splice clamp comprising a curved frame, a lever having a forked end and pivoted intermediate its ends to one end of said frame, said frame and lever being adapted to engage opposite rail splice plates, said forks being outwardly curved and terminating in inwardly directed hook portions, and a pin swingingly and slidably carried by said frame and adapted to pass between said forks.

4. A rail splice clamp as defined in claim 3, wherein the convex surfaces of said lever forks are serrated adjacent said hook portions.

5. A rail splice clamp comprising a frame including a pair of rigidly interconnected and longitudinally curved spaced elongated members, a lever positioned between and pivoted to said members at one end of said frame, one end of said lever being forked, said frame and lever being adapted to engage opposite rail splice plates, a bearing positioned between said members adjacent the other end of said frame and pivoted thereto on an axis parallel to the pivot axis of said lever, and a pin longitudinally slideable in said bearing and adapted to extend between the forks of said lever.

6. A rail splice clamp comprising a curved frame, a lever pivoted to one end of said frame and having a forked portion, said frame and lever being adapted to engage splice plates at opposite sides of a rail, a member pivoted to said frame adjacent the other end thereof, and a pin carried by said member and longitudinally slideable relative thereto, said pin being adapted to swing in the same plate as said lever and to intersect said lever at said forked portion.
